UNITED STATES PATENT OFFICE.

HENRY L. STANTON, OF CHICAGO, ILLINOIS.

DESIGN FOR A SAVINGS-BANK.

51,561.

Specification for Design. Patented Dec. 11, 1917.

Application filed February 20, 1917. Serial No. 149,959. Term of patent 14 years.

To all whom it may concern:

Be it known that I, HENRY L. STANTON, a citizen of the United States, residing at Chicago, in the county of Cook and State of Illinois, have invented a new, original, and ornamental Design for a Savings-Bank, of which the following is a specification, reference being had to the accompanying drawing, forming a part hereof.

Figure 1 is a perspective view of a savings bank in accordance with my new design; and Fig. 2 is a plan view of the same.

I claim:

The ornamental design for a savings bank, as shown.

HENRY L. STANTON.
